Inventor
Wooden Rail by
W. G. Rice, Bucilla City,

United States Patent Office.

WOODSON RICE, OF LONDON, OHIO.

Letters Patent No. 92,646, dated July 13, 1869.

IMPROVEMENT IN SHOCK-TIER.

The Schedule referred to in these Letters Patent and making part of the same.

To all whom it may concern:

Be it known that I, WOODSON RICE, of London, in the county of Madison, and State of Ohio, have invented a new and improved Corn-Compress; and I do hereby declare that the following is a full and exact description of the same, reference being had to the accompanying drawings, and to the letters of reference marked thereon.

This invention relates to a simple contrivance for compressing shocks of corn or other grain, for the purpose of binding them; and consists, mainly, of two stakes, which are connected by means of a strap or chain.

The details of construction and manner of operation will be fully described hereinafter.

In the drawings—

Figure 1 is a perspective view of my invention, attached to a shock of grain, and

Figure 2, a side elevation of the same, detached.

To enable others skilled in the art to make and use my invention, I will proceed to describe fully its construction and operation.

A and B represent stakes, of any suitable size, shape, or material, which are connected by means of the strap or chain C.

These stakes are provided with staples and rings, in order that the strap may be easily attached thereto.

The strap, also, is provided, near each end, with buckles, as shown in fig. 2, by means of which its length may be increased or diminished, at will. If a chain be used, any suitable take-up arrangement may be employed for this purpose.

c represents a swivel, located at the centre of the strap, the use of which will appear hereinafter.

It will be observed that the stake B is provided

with a pin, b, which passes transversely through it, and projects beyond it upon each side.

This invention is especially designed for compressing shocks of corn (although it may be used for other grain) to such compass that they may be bound with a single stalk, thus obviating the annoyance and trouble of binding with several stalks.

The operation is as follows:

The stake B is first thrust into the shock, near its top. (To accomplish this, a short ladder is necessary.) The band is then carried about the shock, and the large end of the stake A is placed over the outer end of the stake B, as is shown in fig. 1 of the drawings. Now, by simply turning the stake A about the stake B, as is indicated in the drawings, the strap or chain C will be wound upon the latter, and the shock will thus be compressed. The swivel in the strap prevents it from becoming twisted. When this operation has been carried far enough, the point of the stake may be thrust under the strap C. In this position it will be securely held, and the operator can proceed to tie the shock. When this is completed, the apparatus is, of course, detached, for further use.

Having thus fully described my invention,

What I claim as new, and desire to secure by Letters Patent, is—

The corn-compress described, consisting of the stakes A B, and strap C, when combined as described, and operated in the manner, and for the purpose set forth.

This specification signed and witnessed, this 30th day of March, 1869.
